RECIPROCATING SAFETY RAZOR

Filed Dec. 31, 1940

UNITED STATES PATENT OFFICE

2,355,830

RECIPROCATING SAFETY RAZOR

Victor T. Van Slyke, Philadelphia, Pa., assignor
to Reciprocating Razors Corporation, Philadel-
phia, Pa.

Application December 31, 1940, Serial No. 372,586

14 Claims. (Cl. 30—46)

This invention relates to an automatically reciprocating safety razor—that is to say a safety razor having a blade arranged to be reciprocated longitudinally by reason of movement of the razor assemblage over the face of the user.

Broadly, one object of the invention is to provide a razor of improved construction over what is shown in the patent to Galt, No. 1,882,007, now owned by the assignee hereof.

One object of the invention is to provide a construction in which all of the parts may be readily produced by automatic machinery, at low cost, and in which the number of parts is reduced to a minimum and which co-operate together without the use of cogs or gears; and in which the parts are so constructed that they may be assembled by instrumentalities other than screw-drivers, wrenches or similar tools, and in which the parts are held together without the use of nuts, bolts, pins, screws, rivets or similar fixed elements. In other words, the object of the invention is to produce an assembly of the fewest possible parts, and the easiest form of assembly, and in which the parts are positive in action and not capable of derangement or displacement under extensive use.

A further, more specific object is to provide a base or assembly frame, which may be formed by an automatic machine instrumentality from a single piece of suitable material and which will rockably support and guide actuating reciprocating levers for the purpose of actuating a blade forming a part of the assembly so that the blade will cut the hair instead of scraping the same.

A further object of the base or assembly frame is to provide means for guiding a retaining lever adapted to operate a slidable blade supporting element in place and to have the end walls of such a supporting frame provide bearing openings, the metal of which is extruded outwardly, the openings being adapted to receive the ends of the actuating rollers and the extruded portions to co-operate with a cover or cap.

A further object is to provide a reciprocable blade holder to be mounted on and guided by the base or frame, above described, and which may be readily stamped from a single piece of suitable material.

A further specific object is to provide a simple locking means to removably secure under tension a form of blade disposed on the blade holder and which readily may be made by automatic machinery and assembled without tools.

A further object of the invention is to provide a cover or cap which acts as a guard in com-

bination with the side rollers and a blade, which guard is provided with integral ears forming a continuation of a stiffening flange at each end of the cap.

In the accompanying drawing, forming a part hereof, is illustrated an embodiment of the invention, in which drawing similar reference characters designate corresponding parts, and in which:

Figure 1 is a perspective view with the cap or cover in elevated position, and the left end portion partly broken away to show the construction;

Figure 2 is a fragmentary detail in perspective, partly broken away, showing the supporting frame to which the handle is attached;

Figure 3 is a fragmentary detail in perspective showing the construction of the handle;

Figure 4 is a fragmentary detail in elevation showing one of the rollers;

Figure 5 is a plan view of the slidable or reciprocable blade holder, part of the locking means being shown in dotted line position in locked arrangement;

Figure 6 is a horizontal section taken centrally and longitudinally through Figure 5;

Figure 7 is a vertical section taken centrally through a portion of the blade holder showing the modified form of locking spring;

Figure 8 is a fragmentary detail in perspective of one corner of the cover plate or cap;

Figure 9 is a plan view of the assembly with the cover cap closed, to show the relationship of the cover cap which forms a guard, the blade and the actuating rollers;

Figure 10 is a plan view of a portion of a form of razor blade adapted to be used with the assembly; and,

Figure 11 is a fragmentary detail in plan of one end of the assembly, the other parts being removed to show the relationship of the cams of the rollers, the actuating levers and the way in which they are supported.

Referring to the drawing, a handle 12 is provided with a series of parallel grooves 13 separated by walls 14, having a series of channels 15, as described in my copending divisional application, Serial No. 426,959, filed January 16, 1942.

The supporting frame 17 is formed from a sheet of suitable material and is provided with a central opening 18 for the insertion of the handle 12, by means of swaging or by means of screw threads. The supporting frame is provided with side walls 19, the ends of which are provided with longitudinal slots 20. The frame 17 is provided with an end wall 21 at each end formed at right

angles to the body of material. The end walls are provided with punched openings 22, that are so made as to produce circular extended projections 23, which are dome shaped for the purpose hereinafter described. Adjacent to each end the body of the frame 17 between the longitudinal walls 19 is provided with drainage openings 63.

In making this part of the assembly it is pressed from a single sheet of material and formed by automatic machinery in the form shown in Figure 2.

In order to form the blade holder a sheet of material is pressed in a plane form. In each end thereof there are formed slots and a downturned lug 25, which is provided with a horizontal lip 26. On each end on the lips 26 there is extruded an upwardly extended boss 27. In forming the downturned lugs 25 there is left on each side of the body horizontally extended ears 28 which at each corner are provided with projecting vertical blade positioning lugs 29.

Intermediate of its ends the body 28 is formed with upwardly extending positioning bosses 30, to fit into suitable openings 31 of the blade 32 (Figure 10). The blade 32 has a central opening 33 for the purposes hereinafter described. The blade has shoulders 34 and adjacent the shoulders are recesses 35. The walls of the recesses 35 fit against the lugs 29 of the blade carrier hereinbefore described.

The body 28 is provided with a longitudinal central depression 36 and the lower face of the body 28 is formed to receive the ends of an arcuate spring 37 of an alloy which is resistant to corrosion.

The body 28 is provided with a central opening 38 through which may be inserted from the bottom a thimble 39, passing through the arcuate spring 37 and through the opening in the body 28 and provided with a flange 40 which bears against the under surface of the spring 37. The thimble 39 is provided with opposite diametrical longitudinal slots 41, adjacent its upper end, so that a key 42 (Figure 6) may be inserted through these slots over the upper surface of the body of material 28. The key 42 is provided with a flat bottom surface 43 and an arcuate upper surface 44. The flat bottom surface 43 is of a size to fit into the central depression 36. In the upper arcuate surface 44 of the key 42 there is provided a plurality of recesses 45 adapted to be engaged by the upper walls of the slots 41. When the key is in position as shown in Figure 6 it will be retained in position and its flat surface will rest in the depression 36.

In the modified means for locking the blade in position, as shown in Figure 7, the thimble 40 and its parts are identical with what is shown in Figure 6, but the locking device takes the form of a spring 46 having depressions 47, the latter of which operate the same as the depressions 45 of the locking key 44 shown in Figure 6. In both forms when the locking elements (44 or 46) are longitudinal with relation to the part 28 the blade 32 is removable. When the locking elements are turned ninety degrees the blade is locked in position as shown in Figure 1.

Coming now to Figures 1, 4 and 11 of the drawing, actuating rolls are formed from a cylindrical body of suitable material, which may be metal or plastic. The rolls are each formed of a cylindrical body having at each end a reduced portion 48, merging in a less reduced portion 49, leaving extending from the body a surface comprised of merging curved portions to produce 75

cams 50. Intermediate of the cams 50 there is formed in the cylindrical body a plurality of grooves 51 formed of merging, curved surfaces, between which grooves there are walls 52, the bases of which walls are thicker than the apices so that greater drainage is afforded. The outer faces of the walls 52 are provided with knurled formations preferably parallel to the longitudinal axis of the cylindrical bodies forming the rolls.

10 Referring more specifically to Figure 11 of the drawing, at each end of the reciprocating blade supporting element 28 there is disposed a lever 54, the ends of which extend through the slots 20 (Figure 2) and each of these levers is provided 15 with an extension 55 at each end arranged to abut the cam surfaces 50 of the actuating rolls. The levers 54 are provided with suitable openings or depressions 54a into which fit the bosses 27 of the lips 26 to afford a fulcrum for the levers 54 when actuated by the cam surfaces 50. The opposite ends of the levers 54 rest against and abut the cam surfaces 50 of the opposite roll. It will be noted that the ends of the levers 54 operate against the cam surfaces of the opposed rollers so that there is a continuity of action without break in reciprocating the blade carrier.

Referring specifically to Figures 1 and 8, the assembly hereinbefore described is covered by a cap 56 which acts as a guard and which is provided at each end with an integral flange 57, each of which flanges terminates at each end in ears 58. The rear side of the cap is provided with openings 59 (Figure 1), the material from the openings being extruded and the front edge being 30 provided through the ears 58 with dome shaped extrusions 60 adapted to fit over the dome shaped extrusions 23 of the openings 22 in the ends of the frame or supporting member 17.

The front edge of the cap or cover 56 is further provided at the corners thereof, with shields or extensions 61, and the ears 58 are provided with downwardly extending extensions or ears 62.

The individual parts as described are first made through the medium of automatic machinery. In the assembly of the finished razor, handle 12 is secured to the blade supporting element 17 in either of the two ways described. The blade supporting element 28 is disposed in the supporting frame so that the downturned horizontally extended flanges 25 and 26 are between the side walls 19 of the supporting frame and the edges of the body 28 abut the side walls 19 which form guides. The actuating levers 54 are disposed so that their ends project through the slots 20 and over the horizontal lips 26 and so that the bosses 27 extend through the openings 54a into the bosses of the levers 54. In that way the ends of the levers 54 extending through the slots 20 maintain the blade carrying element in reciprocal relation to the frame, the downturned portions 25 and 26 of the blade carrying element being retained in position and guided by inner and upper surfaces of the walls 19 of the frame or supporting member. The reduced ends 48 of the rollers are snapped into the openings 22 of the supporting frame 17. The blade 32 is disposed on the holder 28 and the locking element is turned to the position shown in Figure 1.

Further, in the assemblage of the parts, there being no pins, nuts, bolts, or screws, the entire assemblage may be made without tools and when in place cannot be displaced in the practical usage of the device.

The cap 56 is made of a sufficiently resilient material so that, when it is closed, the depre-

sions 60 are disposed over the projections 23, and the cap is under a slight tension. By slight pressure on the ears 62 the cap is released and may be opened to the position shown in Figure 1 of the drawing.

In the proportions designed and as shown in the drawing, the distance between the front edge of the cap 56, and the blade 32, is such that a certain depth of cut will be produced and at the back edge of the device a deeper cut will be assured.

In the operation of the razor the user lathers his face as usual but much less lather than is usual should be used. The razor is applied by pressing the roller 49 against the face with a slow continuous stroke. The roller is caused to rotate performing a number of functions, to wit:

First, by reason of the grooves 51 the lather is spread evenly in front of the blade 32 and is worked backward and forward into the roots of the hair;

Second, the action of the walls of the grooves 51 and their walls is to massage and stretch the skin. The effect of this is to make shaving easier and more comfortable; and,

Third, as roller 53 is rotated the cam surfaces 50 abut the ends 55 of the levers 54 causing reciprocation of the blade carrier 17, the boss 21 thereon projecting through the opening 54a of the blade carrier and forming a fulcrum.

As the blade 32 is reciprocated with its holder it cuts rather than scrapes the hair from the surface treated.

Having thus fully described the invention, what is claimed as new and desired to be secured by United States Letters Patent is:

1. A razor comprising a blade support having end walls and side walls provided with guide slots, rockable levers having their ends disposed through the slots, a blade carrier disposed on the support and pivotally secured to the levers, means for rocking the levers to reciprocate the blade carrier, and a cover pivoted to the support to swing over a blade disposed on said support.

2. A razor comprising a support having end walls and side walls said side walls having guide slots, rockable levers having their ends extending through the slots, a blade carrier disposed on the support and pivotally secured to the levers, rollers journaled to the end walls of the support and provided with cams at their ends abutting the ends of the levers, and a cover pivoted to the support and over the blade support.

3. A razor comprising a frame, a blade carrier disposed on the frame and movable with relation thereto said frame having a central opening, depending and extending flanges at the ends of said carrier, resilient means for securing the blade on the carrier, means carried by the frame for reciprocating the blade carrier and a cover pivoted to the frame.

4. A razor comprising a channel shaped frame, a blade carrier disposed on the frame and movable with relation thereto depending and extending lips at the ends of said carrier, a flanged plug disposed through the carrier adapted to maintain a blade in position thereon, means carried by the frame for reciprocating the blade carrier and a cover hinged to the frame to swing thereover.

5. A razor comprising a support frame, a blade carrier disposed on the support frame and movable with relation thereto said carrier having a central opening, lips extending and depending

from the ends of said carrier, blade positioning bosses on the upper surface of the carrier, a securing element disposed through the carrier, a resilient member disposed through the securing element adapted to maintain a blade in position on the carrier, means carried by the support frame for reciprocating the blade carrier and a cover cap pivoted to the support frame.

6. A razor comprising a supporting element, a reciprocable blade carrier mounted on the supporting element, means carried by the supporting element for reciprocating the carrier, and a resilient cover cap pivoted at one longitudinal edge to one corresponding edge of the supporting element and provided with means at its opposite edge to engage the other edge of the supporting element and provided with guards at its free corners to cover the corners of a blade disposed on said carrier.

7. As an article of manufacture a unit for a razor comprising a supporting element formed from a single sheet of material, having its ends bent upwardly at right angles to the sheet and having its sides bent at an angle to form channel guides provided with guide slots midway the height of their end portions.

8. As an article of manufacture a unit for a razor comprising a supporting element formed from a single sheet of material, having its ends bent upwardly at right angles to the sheet and having its sides bent at an angle to form channel guides provided with guide slots, said end extending outwardly past the sides of the channel, a blade carrier slidably disposed on the supporting element between the guides and blade positioning bosses on its upper surface.

9. As an article of manufacture, a blade carrier for safety razors comprising a sheet of material formed with downreaching lugs centrally of its ends, said lugs being provided with bosses to act as pivots for levers, blade positioning lugs on the upper surface of said material, and a longitudinal depression adapted to receive a blade locking member.

10. A razor comprising a supporting element formed from a single sheet of material having its ends bent at an angle to the sheet and having its sides bent at an angle to form guides said ends projecting outwardly beyond the sides and having perforations in their extremities, a blade carrier comprising a sheet of material formed with downturned lugs disposed between the sides of the supporting element and adapted to be guided thereby, means for reciprocating the carrier, means for securing a blade on the carrier and a cover hinged to said ends to swing over said carrier.

11. A razor comprising a supporting element, a blade carrying element disposed thereon in reciprocable relation thereto and provided with a central opening and a longitudinal depression intersecting the opening, a locking element inserted through the opening, a key disposed through the locking element and adapted to lie in the depression and to be turned at an angle thereto, a curved flat spring for producing a tension on the locking element, means for reciprocating the carrying element, and a cover hinged to overlie the carrying element.

12. A razor comprising a supporting element, a blade carrying element disposed thereon in reciprocable relation thereto and provided with a central opening and a longitudinal depression intersecting the opening, a key disposed through

the opening and adapted to lie in the depression and to be turned at an angle thereto, means for locking the key in a predetermined position, means for reciprocating the carrying element, and a cover disposed to overlay the carrying element.

13. A razor comprising a holder, a blade support carried on said holder, means to move said support reciprocatively, a resilient clamp for removably attaching a blade on said support, and

a cover pivoted to said holder at the corners of one of its longer edges.

14. A razor comprising a holder, a blade support movable reciprocatively in said holder, means for actuating said support, means for resiliently clamping a blade on the support, a cover pivoted to said holder, and resilient means to retain the cover when closed.

VICTOR T. VAN SLYKE.
